WILLIAM R. McKEEN, JR., OF OMAHA, NEBRASKA, ASSIGNOR TO McKEEN MOTOR CAR COMPANY, OF OMAHA, NEBRASKA, A CORPORATION OF NEW JERSEY.

CAR CONSTRUCTION.

1,107,086.

Specification of Letters Patent. Patented Aug. 11, 1914.

Application filed January 17, 1907. Serial No. 352,725.

To all whom it may concern:

Be it known that I, WILLIAM R. McKEEN, Jr., residing at Omaha, in the county of Douglas and State of Nebraska, have invented certain new and useful Improvements in Car Construction, of which the following is a full, clear, and exact description, such as will enable others skilled in the art to which it appertains to make and use the same.

This invention relates to the body construction of railway rolling stock and the like.

One of the objects thereof is to provide a car body of light, rigid construction adapted to withstand without injury all shocks, jars and vibration incident to normal use.

A further object is to provide a structure of the above type characterized by such distribution of the material used and such co-action of the constituent members as to endure abnormal impact and crushing stress, as in the case of railway wrecks, without serious deformation to itself or injury to its contents.

Other independent objects are to provide features of construction of portions of car frames which tend toward the attainment of the above aims irrespective of the relation in which they are used.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings, wherein is shown one of various possible embodiments of my invention,—Figure 1 is a plan thereof, certain parts being broken away in order to show the construction more clearly. Fig. 2 is a similar view in side elevation. Fig. 3 is a plan of certain parts shown in Fig. 1, the same appearing upon a larger scale. Fig. 4 is an end view.

Similar reference characters refer to similar parts throughout the several views of the drawings.

Certain features and aims of this invention will be the more readily understood if the following facts be borne in mind: The

shocks and jars through which the frame of a railway car is loosened and its life shortened fall, in general, at the end of the car, at or about the coupling. If these shocks be localized in one frame element, as the center sill of the floor, there is a tendency to loosen the connections of this member with the remainder of the body, and even if such stresses be transmitted throughout the floor frame, there is a tendency of the upper frame to rock with respect thereto. If these impacts, which are a necessary incident to the life of a car, are to be successfully withstood and rendered harmless, they must be evenly diffused throughout the entire frame and thus received by the whole car body as a unit. Obviously this applies with yet greater force in connection with the abnormal stresses incident to railway wrecks. It may also be noted that in the latter emergency, as the contents of the car are often of more value than the car itself, it is highly important to protect the former from the effects of crushing or fire even though the car be wrecked. The above are among the dominant aims of this invention, and are, among others, attained in constructions of the nature of that hereinafter described.

Referring now to Fig. 1 of the accompanying drawings, there are shown at 1 side sills the ends of which are connected as by end sills 2. Fitted within the inturned flanges 3 of said sills 1, which are preferably of angle cross-section, are car bolsters 4 mounted upon suitable trucks 5. A heavy center sill 6, preferably of I cross-section, passes through the bolsters 4, and secured to each projecting end thereof are spaced members 7 adapted to receive coupling means 8 therebetween. It will be seen that the spaced members 7, which preferably abut against the adjacent bolster, together with the end of sill 6, form rigid means which extend from the end sill to the bolster, and are adapted to transmit any thrust exerted thereon to the latter member. The above construction is substantially identical at both ends of the car, and as the same is in general symmetrical with respect to its transverse axis the details of the structure will be given throughout with reference to one end only.

From end sill 2 outwardly inclined braces 9 extend toward and are connected adjacent the junction of the ends of the bolster 4 with

the side sills 1. Extending from the braces 9 are braces 10 which are inclined outwardly toward and connected adjacent the junction of end sill 2 with the sills 1. A cross member 11 spans the spaced portions 7, and is connected with braces 9 as is best shown in Fig. 3 of the drawings, and these spaced portions are connected with the bolster 4 by the short inclined braces 12.

Bolster 4 is braced from the side sills 1 by the inclined members 13, and the center sill 6 is provided with inclined braces 14 stretched to the side sills throughout the length of the car. It may be noted, however, that these braces 14 are oppositely inclined at opposite ends of the car, as indicated in Fig. 1 of the drawings, and the structure is thus equally well adapted to withstand a shock exerted upon either end thereof.

Needle beams 15 are stretched between the side sills 1, passing beneath the center sill 6, and suitable tie rods 16 also serve to aid in holding the frame elements in proper relation one to another. The latter members acting in conjunction with the inclined braces 14 form in effect rigid triangles which tend materially to stiffen the floor frame of the car and to transmit the stresses to the heavy side sills thereof.

Referring now more specifically to the side framing of the car, there is provided a truss member 17 which is secured to the side sills and projects beneath the same, as shown at 18, thus serving to stiffen these parts in a vertical plane and to provide additional bracing for the door 19, centrally disposed in the car frame. From side sills 1 and truss members 17 a brace 20, preferably of integral form, bridges the door and is secured to the heavy upper side plate 21, the latter being mounted not only upon this member but upon uprights or studs 22 and the inclined braces 23, each of which is stretched, as shown, between the foot of one upright and the upper end of the adjacent upright. It will be noted that as clearly shown in Fig. 2 of the drawings, extensions of the uprights or studs 22 project below the side sills and are connected with the truss member 17.

The roof frame is formed of curved ribs 24, and is covered by sheets 25, the sides of the car being preferably formed of metallic sheets 26.

The end framing as shown in Fig. 4 of the drawings, comprises a pair of uprights 27 and inclined braces 28 stretched from the ends of the end sill toward the end roof rib 24.

The roof is provided with a walk 29, and upon the downwardly curved sides thereof at each side of the roof walk is mounted a rail 30, the same passing through standards 31 riveted to the roof ribs. These rails are

so positioned by reason of the lateral slope of the roof as to be substantially flush with the upper surface of the walk, and thus not to increase the effective height of the car, and are yet of such conformation as to act effectively as guard rails.

The entire construction is preferably of metal, with the exception of the roof walk, and there is provided a metallic door formed of sheets 32 riveted to diagonal and cross braces 33 and 34.

It may here be noted that the expression "center sill" is used throughout this description and the following claims in a broad sense as comprehending not only a single but a multiple element which performs the general functions of a sill and is longitudinally disposed in the floor frame of a car body intermediate the side sills thereof. It may also be noted that the expression "side plate" is used broadly throughout as indicative of a longitudinal member of the upper side frame of a car.

The action of the above-described embodiment of my invention is substantially as follows: Upon any shock being exerted, as at the coupling 8, the same is transmitted by inclined braces 9 and 12 and by the above-described rigid means to the bolster 4, center sill 6 and side sills 1. The impact exerted upon the bolster is transmitted to the side sills not only at its ends but through the short braces 13, and the thrust exerted upon the center sill is evenly diffused throughout the side sills as by the inclined braces 14, this action being identical irrespective of the end of the car at which the blow falls, by reason of the reversely inclined disposition of the braces 14 at opposite ends of the car. From the side sills 1 the shock is transmitted throughout the entire frame by uprights 22 and inclined braces 23, the latter members being likewise oppositely inclined at opposite ends of the car. The bridging truss 20 aids in this action, moreover, and is peculiarly effective by reason of its long bearing against the upper side plate, permitting of the most secure connection at this point. The sheet metal of which the car is formed aids materially in diffusing all impacts thereon, and the transmission of the same to the upper side plate, from which point it is carried throughout the roof by the curved ribs 24 and the metallic sheathing thereon. All tendency of the car to sag, moreover, at its central portion is overcome by reason of the construction of the floor and side frames, the latter portions with the sheathing secured thereto forming in effect plate girders, in which the heavy upper side plate and side sill form respectively the equivalents for the upper and lower flanges. The end framing, moreover, by reason of the disposition of inclined braces 28, tends to do

115
120
125
130

away with any chance of the racking of the frame in a lateral direction, and acting in conjunction with the rigid roof, side and floor frames above referred to, forms a structure which withstands as a unit any stresses brought to bear thereon during the hardest practical use.

It will be seen from the foregoing description that there is produced as a unitary structure, a trussed car body comprising underframe and floor, side and end frames, roof frame, and sheathing for roof and walls, all formed of metal, which as a whole constitutes practically a tubular truss. Normal stresses received either in pulling or in

pushing are transmitted by the coupler and draft gear to the draft sills, and by these and the center sills and diagonal braces to the bolsters, side sills and end sills, and from the side sills and end sills through the uprights and their bracing to the top plate, and finally to the roof members, the diagonal bracing throughout the floor, sides and ends of the car acting to distribute the stresses over the structure, and thus finally to dissipate them without undue stress being concentrated on a part or parts. Very severe or unusually heavy stresses are in part transmitted direct to the end sill by the

horn of the coupler, as usual, and thence distributed as explained. It will further be noted that the metallic plates or sheathing being riveted to the structural or truss members throughout the walls and roof of the car, and being thus held against buckling, contribute enormously to the tying together and bracing or staying of the structural members, and to the strength of the trusses themselves, preventing any bending

or distortion of said structural members, and hence precluding collapse of the trussing of which they form elements. Together with the structural members arranged to constitute trusses, the plates riveted to them produce combined plate and truss girders, and in consequence of the mutual contribution and support so obtained, I am enabled to use structural parts far lighter than would be practicable were not the strength and staying effects of the metal plates or sheathing so availed of.

By reason of the special design and arrangement of parts I am also enabled to utilize almost entirely for the construction of the car, stock material, such as channel and angle bars, I-beams, and plate or sheet metal, without the necessity for the use of a large number of special castings. Not only is the first cost thus reduced but the expense of repair is cut down to a minimum, and repairs may be made without the delay incident to the manufacture or shipping of special parts. The entire frame is not only substantially indestructible as above set forth, but by reason of the disposition of

the metal in a manner to utilize to best advantage its strength, whether subjected to tension or to thrust, or alternately to each, and by so employing the sheathing and uniting it to the structural members as to cause each to prevent distortion or displacement of the other, I am enabled to produce a structure of exceptional strength and capacity to meet all stresses incident to service, while keeping low the total weight of the structure.

The car body so produced possesses in a high degree all the qualities which experience has demonstrated to be desirable in such a structure, and the great rigidity secured, with the consequent freedom from weaving or working of the parts, permits the roof sheathing to be directly and rigidly secured, preferably by riveting, to the roof carlines or members, without liability of causing leakage, a result which has hitherto been unattainable in car construction. Because of the inevitable weaving or working of the parts, it has long been the general custom to avoid rigid attachment of the roof plates or sheathing to the carlines or roof members, and to allow a very considerable degree of play between the roof covering or sheathing and such members.

As many changes could be made in the above construction and many apparently widely different embodiments of this invention could be made without departing from the scope thereof, it is intended that all matter contained in the above description or shewn in the accompanying drawings shall be interpreted as illustrative and not in a limiting sense. It is also to be understood that the language used in the following claims is intended to cover all of the generic and specific features of the invention herein described and all statements of the scope of the invention, which, as a matter of language, might be said to fall therebetween.

Certain features herein shown and described are shown, described and claimed in Letters Patent No. 972,708, dated October 11, 1910, granted to me upon application, Serial No. 361,597, filed March 9, 1907, and hence are not claimed herein.

Having described my invention, what I claim as new and desire to secure by Letters Patent is:

1. In car construction, in combination, side sills, a member stretched between and connected therewith, means connecting said side sills one with another at the end of the car, rigid means extending longitudinally from said last mentioned means to said cross member, and a pair of members connected with said first mentioned means and inclined outwardly toward and connected with said side sills.

2. In car construction, in combination, side sills, a member stretched between and

- connected therewith, means connecting said side sills one with another at the end of the car, rigid means extending longitudinally from said last mentioned means to said cross member, and a pair of members connected with said first mentioned means and inclined outwardly toward said side sills and connected adjacent the junction of said side sills and said cross member.
3. In car construction, in combination, side sills, a bolster stretched between and connected with said side sills, means connecting said side sills one with another at the end of the car, rigid means extending longitudinally from said last mentioned means to said bolster, and a pair of members connected with said first mentioned means and extending outwardly toward said side sills and connected adjacent the junction of said side sills and said bolster.
4. In car construction, in combination, side sills, a bolster stretched between and connected with said side sills, means connecting said side sills one with another at the end of the car, rigid means extending longitudinally from said last mentioned means to said bolster, and a pair of members connected with said first mentioned means and extending outwardly toward said side sills and connected adjacent the junction of said side sills and said bolster, said rigid means comprising a pair of spaced portions adapted to receive coupling means therebetween.
5. In car construction, in combination, side sills, a member stretched between and connected with said side sills, means connecting said side sills one with another at the end of the car, rigid means extending longitudinally from said last mentioned means to said cross member and comprising a pair of spaced portions adapted to receive coupling means therebetween, a pair of members connected with said first mentioned means and inclined outwardly toward said side sills and connected adjacent the junction of said side sills and said cross member, and means connecting said inclined members one with another and spanning the spaced portions of said rigid means.
6. In car construction, in combination, side sills, a member stretched between and connected therewith, an end sill connecting said side sills one with another, rigid means extending longitudinally from said end sill to said cross member, a pair of members connected with said end sill and inclined outwardly toward and connected with said side sills, and a pair of members respectively connected with said last mentioned members and extending therefrom to the points of junction of said end sill and said side sills.
7. In car construction, in combination, side sills, a member stretched between and
- connected therewith, an end sill connecting said side sills one with another, rigid means extending longitudinally from said end sill to said cross member, a pair of members connected with said end sill and inclined outwardly toward and connected with said side sills, a pair of members respectively connected with said last mentioned members and extending therefrom to the points of junction of said end sill and said side sills, 70 said rigid means comprising a pair of spaced portions adapted to receive coupling means therebetween, and a member connecting said first mentioned pair of members one with another and spanning the spaced portions 75 of said rigid means.
8. In car construction, in combination, side sills, a bolster stretched between and connected with said side sills, an end sill connecting said side sills one with another, 80 rigid means extending from said end sill to said bolster and comprising a pair of spaced portions adapted to receive therebetween coupling means, a pair of members connected with said end sill and inclined outwardly 85 toward and connected with said side sills, and a second pair of members respectively connected with said spaced portions of said rigid means and inclined outwardly and connected with said bolster.
9. In car construction, in combination, side sills, a bolster stretched between and connected with said side sills, an end sill connecting said side sills one with another, 90 rigid means extending from said end sill to said bolster and comprising a pair of spaced portions adapted to receive therebetween coupling means, a pair of members connected with said end sill and inclined outwardly 95 toward and connected with said side sills, and a second pair of members respectively connected with said spaced portions of said rigid means and inclined outwardly and connected with said bolster, a pair of members respectively connected with said first mentioned pair of inclined members and extending toward and connecting with the points of junction of said end sill with said side sills, and a member connecting said first pair of members adjacent their points 100 of junction with said last pair of members and spanning the spaced portions of said rigid means.
10. In car construction, in combination, side sills, a bolster stretched between said side sills, a center sill extending through said bolster, and a pair of spaced members secured to said center sill and adapted to receive coupling means therebetween.
11. In car construction, in combination, side sills, a bolster stretched between said side sills, a center sill extending through said bolster, a pair of spaced members secured to said center sill and adapted to receive coupling means therebetween, and a 110

- pair of members connected with said spaced members and inclined outwardly toward and connected with said side sills.
12. In car construction, in combination, a pair of flanged side sills, a center sill of I-
5 cross-section, and inclined braces abutting against and secured to opposite sides of said center sill and resting within the flanges of said side sills and arranged in a general herringbone conformation throughout the
10 length of the car.
13. In car construction, in combination, a pair of side sills, a single center sill therebetween, and braces stretched between and
15 abutting against said center sill and said side sills, and arranged in a general herringbone conformation throughout the length of the car, said braces being oppositely inclined at opposite ends of the car.
14. In car construction, in combination, a pair of side sills, a central longitudinal member therebetween, and braces stretched between and abutting against said central member and said side sills and arranged in
20 a general herringbone conformation throughout the length of the car, said braces being inclined outwardly at each end of the car in a direction from the end toward the center thereof.
15. In car construction, in combination, a center sill of substantially I cross-section, a pair of side sills of angle cross-section, the depth of said center sill being greater than that of said side sills, and cross members
25 resting within the inturned flanges of said side sills and passing downwardly beneath said center sill.
16. In car construction, in combination, a center sill, a pair of side sills, cross members
30 stretched between said side sills and extending beneath said center sill, and inclined braces stretched between said center sill and said side sills.
17. In car construction, in combination, a bolster, side sills, and inclined braces extending from portions of said bolster intermediate its ends to said side sills.
18. In car construction, in combination, a bolster, side sills, inclined braces extending from portions of said bolster intermediate its ends to said side sills, a center sill, and inclined braces extending from said center sill to said side sills.
19. In car construction, in combination, side sills, a bolster, a center sill extending through said bolster, means connecting said side sills one with another at the end of the car, and a pair of rigid members extending longitudinally from said last mentioned
50 means and connected with said center sill, said members being spaced one from another and adapted to receive coupling means therebetween.
20. In car construction, in combination, side sills, a bolster, a center sill extending
65 through said bolster, means connecting said side sills one with another at the end of the car, a pair of rigid members extending longitudinally from said last mentioned means and connected with said center sill, said members being spaced one from another and adapted to receive coupling means therebetween, and inclined braces extending from said center sill to said side sills.
21. In car construction, in combination, side sills, a bolster, a center sill extending through said bolster, means connecting said side sills one with another at the end of the car, a pair of rigid members extending longitudinally from said last mentioned means and connected with said center sill, said members being spaced one from another and adapted to receive coupling means therebetween, inclined braces extending from said center sill to said side sills, and a pair of inclined braces connected with said first
70 mentioned means and inclined outwardly toward said side sills and connected therewith.
22. In car construction, in combination, a side sill, an upper side plate, a pair of upright members extending from said side plate to said side sill and projecting below the side sill, bracing means secured to the lower end of each upright and inclined upwardly to and secured to said side sill at rights, and a bracing member inclined uprights, and a bracing member inclined upwardly from the sill to the plate and thence along said plate and downward to the sill
75 and bridging a side door to the car.
23. In car construction, in combination, a side sill, an upper side plate, a pair of upright members extending from said side plate to said side sill and projecting below the side sill, bracing means secured to the lower end of each upright and inclined upwardly to and secured to said side sill at
80 points spaced from the corresponding uprights, spaced uprights stretched between said sill and said side plate, inclined braces extending from said sill to said side plate between said uprights, and curved roof-supporting members extending from said side plate across to the opposite side of the car.
24. In car construction, in combination, a side sill, an upper side plate, a pair of upright members extending from said side plate to said side sill and projecting below the side sill, bracing means secured to the lower end of each upright and inclined upwardly to and secured to said side sill at
85 points spaced from the corresponding uprights, a bracing member inclined upwardly from the sill to the plate and thence along said plate and downward to the sill and bridging a side door to the car, spaced uprights stretched between said sill and said side plate, inclined braces extending from said sill to said side plate between said up-

- 130

rights, and curved roof-supporting members extending from said side plate across to the opposite side of the car.

25. In car construction, in combination, a side sill, an upper side plate, means forming a side door between said sill and said plate, members extending downwardly from said sill and substantially in alinement with the sides of said door, a truss member extending from said sill downwardly over the ends of said first members and thence inclined upwardly to said sill, and means extending between said first members and said sill, and tending to aid the same in supporting the load upon said sill.

26. In car construction, in combination, a side sill, an upper side plate, means forming a side door between said sill and said plate, members extending downwardly from said sill and substantially in alinement with the sides of said door, a truss member extending from said sill downwardly over the ends of said first members and thence inclined upwardly to said sill, a bracing member inclined upwardly from said sill to said plate and thence along said plate and downwardly inclined to said sill, a plurality of uprights stretched between said sill and said plate, and inclined braces between said uprights extending from said sill to said plate.

27. In car construction, in combination, an end sill, means extending upwardly from each end of said end sill and arched over the car, a pair of uprights stretched between said means and said end sill, and a pair of inwardly inclined braces stretched between said end sill and said means.

28. In car construction, in combination, an upper side plate, roof ribs secured to said side plate and arched upwardly therefrom, and sheathing mounted upon and secured to said roof ribs.

29. In car construction, in combination, a car roof sloping laterally from the center thereof, a walk positioned upon the center of said roof, and a rail positioned upon the lower portions of said roof at each side of said walk.

30. In car construction, in combination, an upper side plate, roof ribs secured to said side plate and arched upwardly therefrom, sheathing secured to said roof ribs, a walk positioned upon the upper portion of said roof ribs, standards mounted upon the lower portion of said roof ribs and secured thereto, and a rail mounted upon said standards.

31. In car construction, in combination, a car roof comprising a plurality of ribs, said roof sloping laterally from its central portion, a walk upon the central portion of said roof, a plurality of standards respectively secured to said ribs at the lower portions thereof, and a rail mounted upon said standards.

32. In car construction, in combination, a

pair of upper side plates, roof ribs arched from one to the other of said side plates, sheathing secured to said roof ribs, an end sill, uprights stretched between said end sill and one of said roof ribs, and inwardly inclined braces connected with said end sill at their lower ends and with said roof ribs at their upper ends.

33. In car construction, in combination, a pair of side sills, end sills connecting said side sills one with another, a pair of side plates, roof-supporting ribs connecting said side plates one with another, uprights stretched between said side sills and said side plates, inclined braces connected with said side sills and said side plates, uprights 75 80 85

stretched between each of said end sills and the corresponding roof rib, and inwardly inclined braces each of which is connected with one of said end sills and the corresponding roof rib.

34. In car construction, in combination, a pair of side sills, end sills connecting said side sills one with another, a pair of side plates, roof-supporting ribs connecting said side plates one with another, uprights stretched between said side sills and said side plates, inclined braces connected with said side sills and said side plates, uprights 90 95

stretched between each of said end sills and the corresponding roof rib, and inwardly inclined braces each of which is connected with one of said end sills and the corresponding roof rib, said first mentioned inclined braces being alternately disposed with respect to said first mentioned uprights, and said second mentioned inclined braces converging in an upward direction toward said second mentioned uprights.

35. In car construction, in combination, a 105 pair of side sills, end sills connecting said side sills one with another, a pair of side plates, roof-supporting ribs connecting said side plates one with another, uprights stretched between said side sills and said side plates, inclined braces connected with said side sills and said side plates, uprights 110 115

stretched between each of said end sills and the corresponding roof rib, inwardly inclined braces each of which is connected with one of said end sills and the corresponding roof rib, and sheathing secured to said roof ribs and said uprights.

36. In car construction, in combination, a 120 side frame comprising a sill and an upper side plate and provided with an opening adapted to form a door, and a member secured to said sill at two points and extending over said opening and secured at its upper portion to said side plate.

37. In car construction, in combination, a sill, an upper side plate, and means secured to said sill at two points and inclined from said sill to said upper side plate and resting against and secured to said side plate.

38. In car construction, in combination, a side frame comprising a sill and an upper side plate and provided with an opening adapted to form a door, and a member secured to said sill at two points end extending over said opening and secured at its upper portion to said side plate, said sill being of substantially constant level throughout the length of the frame. 70
39. In car construction, in combination, a sill, an upper side plate, and means secured to said sill at two points and inclined from said sill to said upper side plate and resting against and secured to said side plate, said sill being of substantially constant level throughout the length of the frame. 75
40. In car construction, in combination, a sill, an upper side plate, a pair of uprights stretched between said sill and said upper side plate, and means secured to said sill and inclined toward and resting directly against and secured to said side plate and extending thence from said side plate to said sill. 80
41. In car construction, in combination, a side frame comprising a sill and an upper side plate and provided with an opening adapted to form a door, a member secured to said sill at two points and extending over said opening and secured at its upper portion to said side plate, said sill being of substantially constant level throughout the length of the frame, and a truss member secured to said sill at either side of said door and depending beneath and spaced from the same below said door. 90
42. In car construction, in combination, side sills, a member stretched between and connected therewith, means connecting said side sills one with another at the end of the car, rigid means extending longitudinally from said last mentioned means to said cross member, a pair of members connected with said first mentioned means and inclined outwardly toward and connected with said side sills, a pair of upper side plates, and inclined braces connected between said sills and the corresponding side plates. 95
43. In car construction, in combination, side sills, a bolster stretched between and connected with said side sills, means connecting said side sills one with another at the end of the car, rigid means extending longitudinally from said last mentioned means to said bolster, a pair of members connected with said first mentioned means and extending outwardly toward said side sills and connected adjacent the junction of said side sills and said bolster, a pair of upper side plates, and inclined braces connected between said sills and the corresponding side plates. 105
44. In car construction, in combination, a center sill, a pair of side sills, inclined braces stretched between said center sill and said
- side sills, a pair of upper side plates, uprights stretched between said side sills and said upper side plates, and inclined braces connected between said side sills and said upper side plates. 110
45. In car construction, in combination, a center sill, a pair of side sills, inclined braces stretched between said center sill and said side sills, a pair of upper side plates, uprights stretched between said side sills and said upper side plates, and inclined braces connected between said side sills and said upper side plates, said second inclined braces being alternately disposed with respect to said uprights and being oppositely inclined at opposite ends of the car. 115
46. In car construction, in combination, a center sill, a pair of side sills, inclined braces stretched between said center sill and said side sills, a pair of upper side plates, a pair of uprights stretched between each of said side sills and the corresponding side plates and adapted to form a door within the side frame of the car, and means secured to each of said side sills at two points and arched over the corresponding door and secured to the corresponding side plate above the same. 120
47. In car construction, in combination, a side sill, an upper side plate, a pair of uprights stretched between said sill and said plate and adapted to form a door therebetween, means secured to said sill at two points and inclined upwardly from each of said points and secured to said side plate, said means bridging said door, and a plurality of inclined braces connected between said sill and said side plate. 125
48. In car construction, in combination, a sill, an upper side plate, a plurality of uprights stretched between said sill and said plate, means connected with said sill at two points and inclined upwardly from each of the same to said plate, said means extending parallel with and secured to said plate, and inclined braces stretched between said sill and said plate intermediate said uprights. 130
49. In car construction, in combination, a sill, an upper side plate, a plurality of uprights stretched between said sill and said plate, means connected with said sill at two points and inclined upwardly from each of the same to said plate, said means extending parallel with and secured to said plate, and inclined braces stretched between said sill and said plate intermediate said uprights, said braces being oppositely inclined at opposite ends of the car. 135
50. In car construction, in combination, a sill, an upper side plate, a plurality of uprights stretched between said sill and said plate, means connected with said sill at two points and inclined upwardly from each of the same to said plate, said means ex-

- tending parallel with and secured to said plate, inclined braces stretched between said sill and said plate intermediate said uprights, said braces being oppositely inclined at opposite ends of the car, roof ribs connected with and arched upwardly from said side plate, a pair of end sills connected with said side sill, and an inclined brace extending from each of said end sills to the corresponding roof rib.
5. In car construction, in combination, a sill, an upper side plate, a plurality of uprights stretched between said sill and said plate, means connected with said sill at two points and inclined upwardly from each of the same to said plate, said means extending parallel with and secured to said plate, inclined braces stretched between said sill and said plate intermediate said uprights, said braces being oppositely inclined at opposite ends of the car, roof ribs connected with and arched upwardly from said side plate, a pair of end sills connected with said side sill, an inclined brace extending from each of said end sills to the corresponding roof rib, a center sill, and inclined braces stretched between said center sill and said side sill substantially throughout the length of the car.
10. In car construction, in combination, an end sill, a pair of spaced draft sills secured to said end sill, a center sill embraced by said draft sills and having said draft sills secured thereto, a pair of side sills, a pair of inclined braces extending from the junction of said end sill and said draft sills to said side sills, a bolster, and a pair of inclined braces secured to said draft sills in advance of said bolster.
15. A car provided with a center sill which consists of a continuous I-beam, and a pair of draft sill members spaced away from each other and having their inner ends bent inwardly so that they embrace the web of the center sill member, substantially as described.
20. In car construction, in combination, an end sill, a pair of spaced draft sills secured to said end sill, a center sill embraced by said draft sills and having said draft sills secured thereto, a pair of side sills, a pair of inclined braces extending from the junction of said end sill and said draft sills to said side sills, a bolster, and a pair of inclined braces secured to said draft sills in advance of said bolster, the inner ends of said draft sills being bent inwardly toward said center sill.
25. In car construction, in combination, a pair of side sills, a bolster of flanged form stretched between said side sills, a single integral center sill of substantially I-cross-section terminating adjacent said bolster, and a pair of relatively spaced draft sills having their inner ends closely embracing and resting substantially against opposite sides of the web of said center sill and secured thereto.
30. In car construction, in combination, a pair of side sills, a bolster of flanged form stretched between said side sills, a single integral center sill of substantially I-cross-section terminating adjacent said bolster, and a pair of relatively spaced draft sills having their inner ends embracing and rigidly connected with opposite sides of the web of said center sill and secured thereto.
35. In car construction, in combination, a pair of side sills, a bolster of flanged form stretched between said side sills, a single integral center sill of substantially I-cross-section terminating adjacent said bolster, and a pair of relatively spaced draft sills having their inner ends embracing and rigidly connected with opposite sides of the web of said center sill and secured thereto.
40. An underframe for cars comprising a single center-sill, and draft-sills the rear ends of which bend toward and lap past the adjacent end of the center-sill.
45. An underframe for cars comprising body-bolsters, a single center-sill disposed between said bolsters, and draft-sills the rear ends of which bend toward and lap past the adjacent end of the center-sill.
50. In car construction, in combination, a bolster; a single integral center sill of substantially I-cross-section terminating adjacent said bolster; and a pair of relatively spaced draft sills having their rear ends arranged to lap past, closely embrace and rest substantially against opposite sides of the adjacent end of said center sill, and secured thereto.
55. In car construction, in combination, a pair of side sills; a bolster of flanged form stretched between said side sills; a single integral center sill of substantially I-cross-section passing through the bolster; and end sill; and a pair of draft sills having their inner ends bent inward, lapping past and rigidly secured to the web of the center sill, and their outer ends extending to and secured to the end sill.
60. In car construction, the combination of a pair of side sills; an end sill connecting the side sills; a bolster of flanged form in cross section; a single integral center sill of substantially I-cross-section passing through the bolster and terminating between the bolster and the end sill; and a pair of draft sills secured at their outer ends to the end sill, spaced apart a distance suitable to receive between them the draft rig, and extending from the end sill toward the bolster to a point in proximity to the end of the center sill, thence extending inward toward

the center sill, and finally lapping past and rigidly secured to the web of the center sill, substantially as described.

63. In car construction, in combination, a pair of metallic side sills; metallic end sills connecting said side sills; an I-beam center sill; bolsters extending from side sill to side sill and secured to said side sills and center sill; and draft sills arranged in pairs at each end of the car, each pair secured to one end sill, extending thence inward parallel with each other and separated to receive between them the draft rigging, thence approaching each other and extending inward past the center sill, and rigidly secured to the web of said center sill.

64. In car construction, the combination of a single center sill of substantially I-cross-section; and draft sills at each end of said

center sill comprising in each instance two 20 metallic members, which at their inner ends lap past and are firmly secured to the web of the center sill, thence separate a distance sufficient to receive between them the draft rigging, and extend thence forward or away 25 from the center sill substantially parallel with each other; whereby stresses received by the draft sills at one end of the car are transmitted directly to the center sill, and through it to the draft sills at the opposite 30 end of the car.

In testimony whereof I affix my signature, in the presence of two witnesses.

WILLIAM R. McKEEN, JR.
